UNITED STATES PATENT OFFICE.

ABRAHAM ADAM SHOBE, OF JERSEYVILLE, ILLINOIS.

CABLE RAILWAY.

SPECIFICATION forming part of Letters Patent No. 361,787, dated April 26, 1887.

Application filed August 6, 1886. Serial No. 210,228. (No model.)

To all whom it may concern:

Be it known that I, ABRAHAM ADAM SHOBE, of Jerseyville, in the county of Jersey and State of Illinois, have invented a new and Improved Cable Railway; and I do hereby declare that the following is a full and exact description of the same, reference being had to the accompanying drawings, and to the letters of reference marked thereon.

10 My invention relates to an improvement in cable railways, particularly of that type employed for street traffic, the cars of which are propelled by an endless cable.

15 The objects of my invention are to provide more simple and efficient means than heretofore for combining large cable-carriers with a small cable-tube, and for draining the cable-tube into suitably-located pits. These objects I attain by means fully explained in the following specification, and illustrated in the accompanying drawings, in which—

Figure 1 is a plan view of the terminus, showing a portion of that part of the road where the two lines unite in one. Fig. 2 is a 25 side elevational view of the same, showing the foundation in section. Fig. 3 is an enlarged transverse sectional view, taken in the line *x* *x*, Fig. 1; and Fig. 4 is an enlarged transverse sectional view, taken in the line *y* *y*, Fig. 1.

30 In the drawings, A represents a pit at the terminus of the road; B B, the two tracks of the railway; C, that part of the road where the two tracks are united in one.

In the pit A is a large return-wheel, *a*, 35 adapted to revolve horizontally upon a vertical spindle, and has upon its periphery a deep groove for the reception of a cable, *d*, which is conducted to and from said wheel by deflecting and guide pulleys *e*, adapted, like the 40 large return-wheel, to revolve horizontally.

Beneath that part of the railway where the tracks are united is a pit, *e*, Fig. 2, in which are cable-carriers *f*, consisting of grooved wheels adapted to revolve upon spindles journaled in iron central supports secured in the foundation of the pit. It is obvious that in lieu of the pit a small tube or tunnel might be employed, either of which would accomplish the same end as the pit, to which, for 45 facility of access, I give preference. Located between the rails of each line, so that the up-

per part is at about the same height as the rails, and central thereto, is a cable-tube, *g*, divided longitudinally, so as to form a narrow slot, *h*, at the top for the grip-arm to travel 55 in, and a wider opening at the bottom for the reception of a gutter, *i*, which, like the two halves of the cable-tube, is sustained by central supports, *J*, which are located at suitable distances apart throughout the whole of that 60 part of the road upon which the cable-tubes are employed.

In order to combine with a small, and consequently inexpensive, cable-tube the advantages of large cable-carriers, the latter are located in the drain-pits *k*, and are journaled in frames supported upon and secured to the floors or foundations thereof, said pits being located at suitable intervals along the line, and adapted not only for the cable-carriers, but to 65 receive the water from the gutters *i*, which may thence be conveyed away to wherever convenient.

It will be observed that the intervals in the continuity of the gutters at the drain-pits 70 form convenient openings in the bottom of the cable-tube for the admission of the upper part of the carrier-wheels.

The tubes *g* terminate at their junction, as indicated at *l*, Fig. 1, and the slots *h* unite 80 near the same point in a single slot in the covering *m* of the pit A, (see Fig. 3,) the central part of said covering being supported by columns *n* and the outer part upon the side walls of the pit.

The cross-ties *b* are made of T-iron inverted and bent into the form of a circular arc, as shown in Fig. 4, so that the backs thereof may, if so preferred, rest upon inverted arches of concrete or masonry, the ends being provided 85 with chairs *o*, surmounted by beams *p*, upon which are secured the rails *q*, the whole connected with the cable-tube by brackets *r*, depending therefrom, to the lower extremities of which the central parts of the ties are bolted, 90 as shown in dotted lines in Fig. 4.

To the top of the cable-tube are secured plates *s*, adapted for lateral adjustment by means of slots *t*, provided for the reception of fastening-bolts, by which said plates are secured to the cable-tube, as shown in Figs. 1 and 4. By this construction the width of the 95

slot can be adjusted to compensate for wear by contact with the grip-arm; and this feature is also employed upon that part of the road where the two lines are united in one, as shown 5 in Fig. 3.

In order to protect the cable-tube against the effect of expansion of the earth or other material with which it is surrounded, it is provided with vertical plates *u*, riveted or bolted to the sides thereof throughout its entire length and reaching high enough to sustain the outer sides of the plates *s*, as shown in longitudinal elevation in Fig. 2 and in transverse section in Fig. 4. It will be observed 15 that the upper edges of these plates being free to vibrate they will yield to the expansion of the contiguous earth or other material and resume their position when the latter contracts, thus relieving the cable-tube of that pressure, 20 which would so contract the slot *h* as to impede the free travel of the grip-arm.

I am aware that a wheel adapted to revolve horizontally in a pit at the end of the track, for the purpose of returning the cable, is not 25 new.

I am aware that the adjustable plates *s* and

yielding plates *u*, shown and described in connection with my cable-tube, are not new, and therefore I do not claim them.

I am also aware that gutters placed beneath 30 the cable-tube for the purpose of draining the same are not new. I therefore do not broadly claim such.

What I do claim as my invention, and desire to secure by Letters Patent, is— 35

The combination, with the cable-tube, of gutters secured in cavities in the tops of the central supports by which the cable-tube is sustained, the separate lengths of said gutters terminating in drain-pits, so as to admit at 40 the intervals in their continuity the upper part of the periphery of the cable-carriers to the interior of the cable-tube, for the purpose set forth.

In testimony that I claim the foregoing I 45 have hereunto set my hand this 21st day of July, 1886.

ABRAHAM ADAM SHOBE.
